UNITED STATES PATENT OFFICE.

MARQUIS H. LOCKWOOD, OF NEW YORK, N. Y., ASSIGNEE, BY MESNE ASSIGNMENTS, TO
PUBLIC SERVICE CUP CO., OF BROOKLYN, NEW YORK, A CORPORATION OF NEW YORK.

SANITARY CUP-DISPENSER.

1,261,947.

Specification of Letters Patent.

Patented Apr. 9, 1918.

Application filed April 28, 1917. Serial No. 165,094.

To all whom it may concern:

Be it known that I, MARQUIS H. Lockwood, a citizen of the United States, and resident of the borough of Manhattan, city, 5 county, and State of New York, have invented certain new and useful Improvements in Sanitary Cup-Dispensers, of which the following is a specification.

My invention has more particular relation to a form of cup dispenser which may be entirely closed when not in use and from which flanged paper cups may be withdrawn from a stack of nested cups one at a time after lifting or removing a suitable 10 cover adapted normally to close the open mouth of the container. Such a container and cup dispensing device is particularly adapted for use in doctors' and dentists' offices or similar places where an uncontaminated clean cup is required from time to time.

Preferably the container for the cups is an upright open mouth jar or can provided with a removable lid or cover and the cup 15 releasing or separating device is adapted to operate on nested, flanged paper cups placed in the container in an inverted position.

Preferably I provide a plurality of circumferentially disposed resilient fingers extending parallel with the axis of the stack of cups, between the cups and the wall of the container and adapted for longitudinal movement. The outer ends of the fingers 20 are provided with knobs, lugs, or noses projecting radially inward in position to be engaged by the flange of the topmost cup when the latter is lifted by grasping the bottom thereof with the fingers. The cup flanges fit closely within the circumferentially arranged spring fingers and the latter lie closely along the wall of the container, so that when the top cup is lifted until the flange thereof engages the noses or knobs 25 on the upper ends of the fingers the fingers can be bodily lifted or moved outward. This result is accomplished because the knobs or noses on the upper ends of the fingers preferably, normally lie within the 30 mouth of the container and even though the fingers are preferably flexible or resilient they can not be moved radially by the pressure of the cup flange until the ends of the fingers are drawn out of the mouth of the 35 container. In order to release the cup the

fingers, or at least the upper ends thereof, are adapted to be flexed or bent out over the edge of the mouth of the container until the flange of the top cup can pass the knobs or noses and become released.

The fingers are preferably retractile, that is they are mounted so that they will automatically be drawn back to their normal position within the mouth of the container after they have been drawn out and flexed 60 over the edge of the container to release the topmost cup. If a second cup of the stack should stick to the top cup as the latter is withdrawn, the knobs or noses on the ends of the fingers would engage the flange of the 65 second cup and loosen it from the first or top cup by the impact of the knobs as the fingers are retracted. In order to retract the fingers simultaneously, they are preferably secured at their lower ends to a metal 70 disk which is heavy enough to give the required retractile force. The disk and attached fingers preferably fit loosely in the container thereby permitting them to be readily removed to clean the container or to 75 place therein a fresh supply of cups.

My improved cup dispenser is quite simple as will be seen from the accompanying drawings in which Figure 1 shows the covered container in vertical section; Fig. 2 85 represents the container in vertical section with lid removed and the top cup in position for release; Fig. 3 is a top plan view of the device with cover removed from the container; Fig. 4 is a separate view of the 90 spring finger assembly; Fig. 5 is a sectional detail of the attachment of a spring finger to the disk; Fig. 6 is a detail of the nose or upper end of the spring fingers when tipped with a ball, and Fig. 7 shows a modified 95 form of nose for the upper ends of the spring fingers.

Referring to the drawings it will be seen that my improved cup dispenser is small and compact and adapted to hold about one 100 dozen cups although, obviously, it can be made larger.

Preferably I provide an upright cylindrical jar or can 1 of metal, celluloid, glass or other suitable material. The inner wall 105 is preferably smooth and the open mouth of the container is at the top and adapted for the removal of the cups therethrough. The mouth may be covered in order to keep out dust and prevent contamination of the 110

cups, the cover being of any suitable character such as the lid 2 provided with an annular flange or ring 3 of larger diameter to telescope over the mouth of the container 5 1 as illustrated in Fig. 1.

The cups used are preferably the well known "Lily" cups 4 provided with an outwardly curved flange 5 at the mouth of the cup. The cups are frusto-conical and nested 10 to form a stack. The diameter of the container 1 is preferably slightly greater (about $\frac{1}{16}$ of an inch) than the cup flanges 5. If paper cups of this character are to be dispensed properly, some means must be provided for loosening the cups so that they can 15 be separated one at a time. For this purpose I preferably provide a plurality of retractile fingers 6 of resilient material adapted to lie between the stack of cups and the 20 wall of the container 1. In the form shown in the drawings three fingers 6 are circumferentially spaced about the stack of cups 4 and lie parallel with the axis thereof.

The fingers 6 are preferably narrow strips 25 of thin spring steel although brass or other suitable material may be used. The upper ends of the fingers are preferably provided with knobs or noses adapted to extend radially inward and overhang the flange of 30 the topmost cup. As shown in Figs. 1 to 6 of the drawings, I prefer to form the noses on the ends of the resilient fingers by attaching to the ends thereof a small metal sphere or ball 7.

In order that the finger may lie close to 35 the wall of the container the upper end of each finger 6 is preferably bent at 8 at an angle of about 45° and enters a slot in the ball. The ball is then secured to the finger 40 by solder or otherwise. The outer point of the ball 7 is thus about on a line with the outer face of the finger and adapted to rest or be pressed against the inner wall of the container. If desired a half-round cylindrical nose 7^a (see Fig. 7) may be used if 45 for any reason it should be preferred. The nose might be integral or otherwise attached to the finger but the forms shown are preferable as being more sanitary in that they 50 offer fewer recesses for the accumulation of dirt or bacteria. The upper ends of the retractile fingers 6 normally lie just within the mouth of the cup as illustrated in Fig. 1 of the drawings. When in this position, it 55 will be seen that the flange 5 of the top cup will engage the balls or noses 7 if an attempt is made to remove the cup from the container 1. When this occurs the retractile fingers 6 are adapted to be drawn along 60 with the cup until the balls or noses get well beyond the edge of the container mouth. The upper ends of the fingers 6 are adapted to be bent radially outward in any suitable way by the pressure of the cup flange 65 against the noses 7 and thus permit the re-

lease of the cup. For this reason I preferably make the fingers or at least the upper ends thereof quite flexible. When the top cup and the fingers 6 are drawn up to the position shown in Fig. 2 the pressure of 70 the cup flange on the noses will flex the fingers over the edge of the container thereby permitting release of the cup.

I have mentioned that the fingers 6 are retractile and they may be made so in any 75 suitable or preferred manner. To avoid the use of springs for retracting the finger 6, I preferably secure the lower ends of the finger to a heavy metal disk 9 the weight of which is sufficient to quickly draw down 80 the fingers after releasing the top cup as herein before described. The flexibility of the fingers together with the retraction thereof will cause the noses or balls 7 to move downward and inward below the 85 flange of the released cup and engage or be in position to engage the flange of the succeeding cup. If the succeeding cup sticks to the top cup the blow of the noses 7 on the flange thereof will be sufficient to loosen the 90 cup and permit it to drop back into the container. At the same time the fingers 6 will return to normal position as shown in Fig. 1 of the drawings.

The lower ends of the fingers 6 may be 95 secured to the disk 9 in any suitable or preferred manner. Preferably however, I will transverse slots in the edge of the disk 9 of a width equal to the width of the spring metal used. The slots are deeper than the thickness of the metal of the fingers so that the latter can be secured therein by peening the metal of the disk over the edges of the fingers as will be more particularly seen at 100 10 in Fig. 5 of the drawings. To more firmly secure the fingers 6 to the disk 9 the lower ends of the fingers at 11 may be bent at right angles so as to lie in contact with the under face of the disk 9 where they may 105 be soldered or otherwise secured.

By mounting the fingers 6 upon the disk 9 they become a unit and can be removed and replaced readily and the inside of the container may be kept clean and free from bacteria.

The cups are placed in the container by first removing the spring finger unit and slipping the stack of cups in between the fingers until the lower cup rests on the disk 9. The stack of cups with the fingers and disk are then dropped into the container where they will assume the position shown in Fig. 1 of the drawings. When the cover 2 is over the container the cups will be kept 120 from dust or other contamination. When a cup is required the cover is removed and the top cup is grasped in the fingers and lifted straight up. As the flange of the top cup nears the mouth of the container, it will 125 engage the noses or balls 7 and the fingers 6 130

together with the disk 9 and the balance of the stack of cups resting thereon will be lifted until the pressure of the flange of the top cup forces the balls 6 outward by flexing 5 the fingers over the edge of the mouth of the container and permits the release of the cup (see Fig. 2).

It will be understood that various modifications in the specific detail of construction 10 may be made without departing from the spirit and scope of the invention. For instance the retractile fingers may be hinged or flexibly attached at a particular place near the upper ends thereof or made entirely 15 integral as preferred and they may be united and retracted in various ways.

I claim:

1. A dispenser for flanged paper cups comprising an open mouthed container and 20 retractile fingers parallel with the axis of the container adapted by engagement with the flange of a cup in withdrawing the same to be moved axially of the container and flexed over the edge of the mouth of said 25 container to release the cup.

2. A dispenser for flanged paper cups comprising an open mouthed container, retractile fingers parallel with the axis of the container adapted by engagement with the 30 flange of a cup in withdrawing the same to be moved axially of the container and flexed over the edge of the mouth of said container to release the cup and means adapted to retract said fingers after the release of the cup.

3. A dispenser for flanged paper cups comprising an open mouthed container, a plurality of retractile fingers movable parallel with the axis of the container, noses on said fingers adapted to be engaged by the 40 flange of a cup in withdrawing the same whereby said fingers are drawn outward and flexed over the edge of said container to release the cup and means for retracting said fingers.

4. A dispenser for flanged paper cups comprising an open mouthed container, retractile fingers parallel with the axis of the container adapted to lie between the cups and the wall of said container, means 45 extending transversely of the container below the cups for connecting said fingers to move

in unison and noses on the ends of said fingers adapted to be engaged by the flange of a cup in withdrawing the same from the container, said fingers being adapted to be 55 drawn out of the mouth of the container and flexed over the edge thereof to release said cup.

5. A dispenser for flanged paper cups comprising an open mouthed container, a 60 plurality of circumferentially spaced retractile fingers adapted to extend toward the mouth of said container between the wall thereof and the cups, means adapted to retract said fingers so that the upper ends 65 thereof are normally within the mouth of said container, and knobs or noses on the ends of said fingers adapted to be engaged by the flange of a cup in withdrawing the same, whereby said fingers are drawn out of 70 the mouth of the container and flexed over the edge thereof to release the cup, said fingers being retracted to normal position after the release of the cup.

6. A dispenser for flanged paper cups 75 comprising an open mouthed container adapted to hold a stack of nested cups, a plurality of retractile, flexible fingers spaced circumferentially within the container about the stack of cups and provided with radially 80 projecting noses adapted to be engaged by the flange of a cup in withdrawing the same from the stack, said fingers being drawn out of the mouth of the container and flexed over the edge thereof to release the cup. 85

7. A dispenser for flanged paper cups comprising an open mouthed container adapted to hold a stack of nested cups, a plurality of retractile, flexible fingers spaced circumferentially within the container about 90 the stack of cups and provided with radially projecting noses adapted to be engaged by the flange of a cup in withdrawing the same from the stack, said fingers, when thus engaged by the flange of a cup, being adapted 95 to be drawn out of the mouth of the container and flexed over the edge thereof to release said cup and means for retracting said fingers whereby said noses are adapted to engage the succeeding cup of the stack. 100

MARQUIS H. LOCKWOOD.
